UNITED STATES PATENT OFFICE.

ARTHUR B. CHRISTOPHER, OF ST. LOUIS, MISSOURI.

DESIGN FOR AN INDICATOR.

60,085.

Specification for Design.

Patented Dec. 27, 1921.

Application filed July 2, 1921. Serial No. 482,222. Term of patent 14 years.

To all whom it may concern:

Be it known that I, ARTHUR B. CHRISTOPHER, a citizen of the United States, residing in the city of St. Louis, and State of Missouri, have invented a new, original, and ornamental Design for Indicators, of which the following is a specification, reference being had to the accompanying drawing, forming part thereof.

The drawing is a front elevation of an indicator showing my new design.

I claim:

The ornamental design for an indicator, as shown.

ARTHUR B. CHRISTOPHER.
